HARRY E. DUNKELBERGER AND NICK WINTERS, OF WEIRTON, WEST VIRGINIA

CLAMSHELL BUCKET

Application filed November 1, 1929. Serial No. 404,080.

This invention relates broadly to dredges, scoops and like excavating apparatus, and more specifically to grab-buckets for such apparatus.

5 The primary object of the invention is to provide a grab-bucket of so-called clam-shell type which embodies in or at the bottom of each of the relatively reciprocable or cooperating bucket sections or jaws thereof a blade 10 which has a beveled or sharpened working edge, which is detachable for re-sharpening of said edge, and which may be adjusted from time to time, as following each re-sharpening, for presenting said blade in a projecting 15 working position.

It will be understood that, in the usual commercial forms of clam-shell buckets, each of the jaws is ordinarily provided with a bottom of which the forward edge is subjected to rapid wear in the handling of material and, therefore, frequent renewals of the bottom and sides of the bucket jaws is required. Moreover, where rock, slag, or other such material is being handled, the beveled 25 edges of the jaw-bottoms quickly become dulled, or worn down, to the extent that the bucket jaws do not readily enter the material.

As above indicated, an object of the present 30 invention is to provide, in association with each of the bucket jaws, a blade which may have its edge re-sharpened as and when required and which, as it becomes worn, may be shifted, or advanced, from time to time for presenting said edge in working position, with the end in view to obviate the necessity for frequent renewals of the bottoms of the jaws required in the use of clam-shell buckets 35 of the present commercial forms.

40 In describing the invention in detail, reference is herein had to the accompanying drawings, in which—

Figure 1 is a side elevation of a clam-shell bucket constructed in accordance with our 45 invention, said bucket being shown with its jaws occupying open position;

Figure 2 is a top plan view of the same;

Figure 3 is an end elevation of the same; and—

50 Figure 4 is a section on line 4—4, Fig. 2.

Referring to said drawings, 1 designates the side walls, and 2 the bottoms of the two relatively reciprocable pivoted jaws of a clam-shell bucket of a common type, said bottoms being attached to inturned outer edge portions or flanges 3 of said side walls, as by means of rivets 4. The side walls 1 and the bottom 2 of each of the jaws are supplemented by an enclosing plate 5 which occupies upwardly inclined relation to said bottom and which is attached, as by rivets 6, to correspondingly inclined edge portions 7 of said side walls.

55 Interposed between the bottom 2 and the adjacent edge of the plate 5 of each jaw and occupying a position in which it rests against the inner face of said bottom is a rectangular blade 8 having its forward edge 8^a projecting outwardly beyond the corresponding edge of said bottom such a distance that it, rather than said bottom, constitutes the cutting and wear-receiving element of the bucket. Said projecting edges 8^a are preferably beveled to facilitate the entering of the bucket jaws in 60 the material which is being handled.

65 The blade 8 has its lateral edge portions so located with respect to the flanges 3 of the sides 1 that attaching bolts 9 directed through said lateral edge portions, the bottom 2, and said flanges 3 serve to secure it rigidly in place. For the reception of said attaching bolts 9 a plurality of symmetrically spaced holes 10 are provided in said flanges, in the opposite lateral edges of the bottom and in the lateral edges of the blade. Said blade has a vertical width which, initially, is preferably greater than that of the bottom 2, having its outer end projecting 70 outward between said bottom and the adjacent edge of the plate 5, as shown. When the cutting edge of the blade has been worn away, the latter may be removed, re-sharpened, and then replaced with its said edge disposed in projecting relation to the corresponding edge of the bottom. The lines of symmetrical holes 10 in the blade are continued throughout the vertical width of the latter, thus to permit of numerous advance 75

80 shiftings, or adjustments, until the blade 85 is in the desired position. The side walls 1 and the enclosing plate 5 are provided with 85

shall have become worn away substantially in its entirety.

What is claimed is—

1. In a clam-shell bucket, jaws comprising side walls having inwardly turned end flanges, a bottom permanently attached to said flanges, and a blade removably mounted against the inner face of said bottom and having a beveled edge, said blade normally having its said edge projecting forwardly with respect to the inner edge of said bottom and being adapted to be advanced from time to time, the lateral edges of said blade being provided with lines of symmetrically spaced bolt-receiving holes.
2. In a clam-shell bucket, jaws comprising side walls having inwardly turned end flanges, a bottom permanently attached to said flanges, a plate supplementing said bottom, said plate being disposed at an angle to said bottom and having its inner edge spaced from the outer edge of the latter, and a blade removably mounted on the inner face of said bottom, said blade having a cutting edge normally projecting forwardly with respect to the front edge of said bottom and having its opposite edge portion extending outwardly between said bottom and said plate, said blade being adapted to be shifted to an advanced position when its cutting edge becomes worn.

In testimony whereof we affix our signatures.

HARRY E. DUNKELBERGER.
NICK WINTERS.
